Patented Jan. 5, 1965

200,002

DOOR KNOB

Marron Kendrick, Atherton, Calif., assignor to
Schlage Lock Company, a corporation

Filed July 31, 1964, Ser. No. 81,094

Term of patent 14 years

(Cl. D50—3)

FIG. 1.

FIG. 2.

FIG. 3.

FIGURE 1 is a side elevation of a door knob showing the design of my invention;

FIGURE 2 is a front elevation of the door knob shown in FIGURE 1; and

FIGURE 3 is a cross section on an axial plane through the door knob of my invention.

I claim:

The ornamental design for a door knob, as shown.
